UNITED STATES PATENT OFFICE

147,226

DESIGN FOR A SPRAYER

Henry E. Brandt, North St. Paul, Minn.

Application October 6, 1945, Serial No. 122,610

Term of patent 14 years

(Cl. D62—2)

To all whom it may concern:

Be it known that I, Henry E. Brandt, a citizen of the United States, residing at 216 19th Ave. N. E., North St. Paul, in the county of Ramsey and State of Minnesota, have invented a new, original, and ornamental Design for Sprayer, of which the following is a specification, reference being had to the accompanying drawing, forming part thereof.

Fig. 1 is a view in front elevation of the sprayer showing my new design;

Fig. 2 is a top plan view of the sprayer;

Fig. 3 is a view in side elevation as seen from the right of Fig. 1; and

Fig. 4 is a view partly in front elevation and partly in central vertical section for showing the depression in the top of the sprayer container.

I claim:

The ornamental design for a sprayer, as shown.
HENRY E. BRANDT.
